Inventor

J.E. BLALOCK

UNITED STATES PATENT OFFICE.

JOSEPH E. BLALOCK, OF SALISBURY, NORTH CAROLINA.

CAR-DOOR FASTENER.

Application filed June 2, 1921. Serial No. 474,538.

To all whom it may concern:

Be it known that I, JOSEPH E. BLALOCK, a citizen of the United States, residing at Salisbury, in the county of Rowan and 5 State of North Carolina, have invented certain new and useful Improvements in Car-Door Fasteners, of which the following is a specification.

This invention relates to car door fasteners, and more specifically, to an improved locking and sealing device for a sliding door such as used on railway-freight-cars.

One object is to provide an improved locking and sealing device which automatically locks and seals doors upon closing the door after a sealing strip has been properly attached thereto.

Another object is to provide an improved, yet very simple auxiliary lock or latch and 20 a simple and easily operated means for unlocking or unlatching the door.

Another object is to provide an improved tubular track which is weather-proof against invasion by birds such as might build their 25 nests therein, if permitted, and cause a difficulty in moving the door along the track.

Other objects and advantages will be pointed out or implied in the following details of description in connection with the 30 accompanying drawings in which:

Fig. 1 is an elevation illustrating a portion of a car embodying my improved car door fastener and track, portions being broken away to disclose other portions, the 35 door being open.

Fig. 2 is a view somewhat similar to Fig. 1, but the door being closed, a portion of the unlocking or unlatching lever being broken off.

Fig. 3 is a sectional view along the line 5-5 of Fig. 1.

Fig. 4 is a horizontal sectional view along the line 6-6 of Fig. 1.

Fig. 5 is an enlarged detail view showing 45 the seal or sealing strip being closed or looped and locked through a part of the locking or sealing mechanism.

Fig. 6 is an enlarged section view through the seal holder, the section being taken along 50 the line 6-6 of Fig. 2.

Referring to these drawings in detail, in which similar reference characters correspond with similar parts throughout the several views, the invention consists in the 55 construction, combination and arrangement

of parts as will now be fully described as follows.

The reference character 1 generally indicates the side of a car which has a door-opening or frame 2. A tubular track 3 is 60 secured to the car by means of bolts 4, and the ends of this tubular track are closed by blocks 5 through which certain of the bolts 4 extend, thereby closing the ends of the tubular track for preventing rain, snow, hail 65 and other foreign matter from entering the track. This track is formed with a slot 6, and on opposite sides of this slot a pair of flanges 7 provide ways or track elements 70 on which a pair of rollers 8 travel, these rollers being pivoted or journaled, in pairs, on opposite sides of hangers 9 which are bolted or otherwise secured to a door 10 which is adapted to close the door-opening 2. An upright beam 11 extends down from 75 one end of the track 3 and provides an abutment to limit the opening movement of the door, and a tongue or clip 12 of spring metal is secured on the beam 11 and presses against the outer surface of the door 80 to frictionally hold it against closing when it is in its fully open position.

An upright beam 13 extends down from the other end of the track 3 and provides an abutment for limiting the closing movement of the door. The beams 11 and 13 are secured to the car by any appropriate means (not shown); and a guide-rail 14 has its ends bolted or otherwise secured to the lower ends of these upright beams. 90 Moreover, brackets 15 are secured to the car and to the guide-rail 13 for holding the latter in spaced relation to the side of the car.

The locking and sealing mechanism will 95 now be described as follows:

A plate 16 is bolted or otherwise secured to the beam 13, and this plate is provided with horizontal projections or lugs 17 and 18 which are provided with openings 19 and 20. 100 Moreover, the plate 16 is provided with a pair of bearings 21 through which a plunger 22 is mounted to reciprocate up and down. It is to be understood that the elements 17, 18 and 21 may be either formed integrally with 105 the plate 16 or secured thereto by any appropriate means. The plunger 22 has a collar or spring-seat 23 secured thereto, and a spring 24 is compressed between the spring-seat 23 and the lower bearing 21, so 110

that it continually presses the plunger 22 upward. A seal holder 25 is secured on the plate 16, being preferably pivoted as indicated at 26, and any appropriate means may 5 be employed for limiting the rotary movement of the seal holder upon its pivot. This seal holder, as best shown in Figs. 5 and 6, is provided with an aperture 26^a through which the pivot 26 extends, and is also provided 10 with an upwardly and inwardly extending flange 26^b which engages with an outwardly extending flange 27 of the sealing strip 28. This sealing strip is of a well known type and includes a shoulder 28^a which engages 15 with a spring catch 28^b when the seal is closed, and the seal cannot be opened without breaking it. A shoulder 28^c of the sealing strip rests against the lower end of 20 plunger 22 while the adjacent portion of the strip 28 clamped in the bifurcated lower end of the plunger 22. One of the furcations of the plunger 22 is indicated at 22^a, Fig. 5, and the slot between these furcations, which receives the strip 28, is indicated at 25 22^b in Fig. 3.

A keeper 29 is provided with a slot or aperture 29^a which is vertically aligned with the plunger 22 when the door is closed, this keeper being secured on the door by bolts or 30 other appropriate means. A lever 30 is pivoted to the plunger 22 at 31, and pivoted to the beam 13 at 32. This lever is preferably in the form of a bell-crank, and is actuated by means of a plate or pusher 33 for 35 thrusting the plunger 22 downward, upon closing the door. The upper and lower ends of a casing 34 fits snugly about the upper and lower bearings 21 and protect the spring 24.

40 The operation of the device, as thus far described, is as follows.

Preparatory to closing and sealing the door, the operator first inserts the flange 27 in the holder 25, next inserts the portion adjacent to the shoulder 28^c in the slot 22^b, or between the furcations 22^a, with the shoulder 28^a in position to enter the hollow element which contains the catch 28^b, and then pushes the door leftward so that its pusher 33 50 swings the lever 30 so as to thrust the plunger 22 downward through the slot 29^a, thereby pushing the shoulder 28^a into engagement with the catch 28^b. As the door closes, the keeper 29 enters and projects 55 through the apertured lug 17 and passes by the end portion of the strip 28 which is seated in the holder 25; and therefore, when the plunger 22 carries the other end of the sealing strip through the openings 20 and 29^a, it loops the sealing strip around the material at one side of each of these openings, thereby sealing the door.

The reaction of the spring 24, after the closing of the door tends to open the door, 60 acting through the medium of the plunger

22, lever 30 and pusher 33; and in order to offset this tendency to open the door, I provide a spring pressed bolt 35 which extends through a bolt-seat 36 in the wall 1 of the car. An apertured plate 37 is secured to said 70 wall and comprises a portion of the bolt-seat or bearing. A yoke 38 also comprises a portion of this bolt-seat, being provided with an aperture 39 through which the inner end of the bolt extends. The bolt 35 is provided with a shoulder, preferably having a washer fitted thereon, and a spring 40 is compressed between said washer and yoke so as to continually press the bolt 35 outward. The elements 35 to 40 inclusive 75 constitute a supplemental or auxiliary locking device. A lever 41 is fulcrumed or pivoted in bearing 42 on the car-door 10, and the lower end of the lever 41 is preferably bent outward for convenience in quickly and 80 easily grasping this lever or handle of the lever so as to swing its upper arm 41^a inward against the bolt 35 for pressing it out of its locking engagement with the door 10.

A metal strip 43 is secured on the inner surface of the door by any appropriate means (not shown), and this strip serves as a track which slides against the bolt 35 when the door is being closed and opened, thereby holding the bolt depressed or in its effective 90 position. However, as soon as the door leaves its fully closed position, the spring 40 presses the bolt 35 outward against the rear end of the door and effectually prevents opening of the door until it is depressed. The bolt 35 may be depressed by pulling the lower end of the lever 41 outward and upward, so that its upper end presses the bolt 35 inward. As soon as the door is released from the bolt 35, the spring 24 pushes or 95 assists in pushing the door open in the manner previously explained. The locking or bolting mechanism which includes the bolt 35 is preferably located between two uprights 44 and 45 which support the wall 1 100 adjacent to the door opening.

A handle 46 may be provided on the door for convenience in opening and closing.

It is not intended to limit this invention to the exact details of construction and arrangement as here illustrated, but changes may be made within the scope of the inventive ideas as implied and claimed.

What I claim is:

1. The combination of a door, an apertured keeper therefor, a sealing mechanism adjacent to the door opening and including a plunger movable through said keeper, said sealing mechanism being formed with an opening through which said keeper projects when the door is closed, a holder for a sealing strip, and means on the door to actuate said plunger and cause it to co-act with said holder for looping and locking the sealing strip through said keeper.

2. The combination with a car door and its frame, of a lock comprising a plunger held to said frame, a spring normally pressing said plunger upward, a keeper held to said door having a slot vertically aligned with said plunger, a pivoted bell crank slidably held to said plunger, a pair of apertured lugs held to said frame below said plunger, said keeper arranged to pass through said apertures, and a push plate held to said door for engagement with said bell crank for holding said door in locked condition.
3. The combination with a car door and its frame, of a lock comprising a plunger held to said frame, a spring normally pressing said plunger upward, a keeper held to said door having a slot vertically aligned with said plunger, a pivoted bell crank slidably held to said plunger, a pair of apertured lugs held to said frame below said
- plunger, said keeper arranged to pass through said apertures, a seal holder pivoted below said plunger having an outstanding flange, a sealing strip arranged to be held by said holder and said flange for looping and locking said strip through said keeper, and a push plate held to said door, as and for the purpose set forth.
4. In combination with a car door, of a housing, a plunger vertically reciprocating in said housing said plunger projecting beyond the ends of said housing, a spring in said housing to normally force said plunger upward, a keeper fixed to said door arranged to be engaged by said plunger, and a bell crank held to said plunger, said spring and bell crank being adapted to cushion the closing of said door and assist in opening the door.

In testimony whereof I affix my signature.
JOSEPH E. BLALOCK.
